UNITED STATES PATENT OFFICE.

HIAL S. GRANNIS, OF SOUTHINGTON, CONNECTICUT, ASSIGNOR TO THE PECK, STOW & WILCOX COMPANY, OF SAME PLACE.

DESIGN FOR A FRAME FOR GROOVING-MACHINES.

SPECIFICATION forming part of Design No. 26,806, dated March 23, 1897.

Application filed February 4, 1897. Serial No. 622,049. Term of patent 7 years.

To all whom it may concern:

Be it known that I, HIAL S. GRANNIS, a citizen of the United States, residing at Southington, in the county of Hartford and State of Connecticut, have invented and produced a new and original Design for a Grooving-Machine Frame, of which the following is a specification, reference being had to the accompanying drawings, in which—

Figure 1 is a side elevation of a grooving-machine frame, showing my design; and Fig. 2 is an end view of the same, showing the left-hand end.

The design relates to that class of grooving-machines in which the frame has a straight bar with parallel sides and edges extending along the upper portion of the frame.

A designates the upper bar, B the horn,

and C the body, of the frame. The top edge of the frame-body C is straight and flush with the top of the bar A. The said bar is ribbed, as at 3, on each side adjacent to its top and bottom edges. The body on each side is thickened at the shoulder 4, the top of which shoulder is about level with the top of the lower rib 3 of the bar. The bar A is secured within the upper portion of the body C by the bolts 5 and nuts 6, which show on the respective sides.

I claim—

The design for a grooving-machine frame substantially as herein shown and described.

HIAL S. GRANNIS.
